UNITED STATES PATENT OFFICE.

LLOYD JONES, OF PITTSBURGH, PENNSYLVANIA, ASSIGNOR TO UNITED ENGINEERING AND FOUNDRY COMPANY, OF PITTSBURGH, PENNSYLVANIA, A CORPORATION OF PENNSYLVANIA.

UNIVERSAL COUPLING.

1,271,905.

Specification of Letters Patent. Patented July 9, 1918.

Application filed December 20, 1917. Serial No. 208,159.

To all whom it may concern:
Be it known that I, LLOYD JONES, a citizen of the United States, residing at Pittsburgh, Allegheny county, Pennsylvania, have invented a new and useful Improvement 5 in Universal Couplings, of which the following is a full, clear, and exact description, reference being had to the accompanying drawings, forming part of this specification, in which:—

Figure 1 is a side elevation, partly in section, of a rolling mill drive embodying the invention.

Fig. 2 is a plan view of the coupling spindle.

Fig. 3 is a vertical section through the coupling.

Fig. 4 is a section on the line IV—IV of Fig. 3.

Figs. 5 and 6 are a plan view and longitudinal section, respectively, of the wear plate in which the shoes are mounted.

Figs. 7 and 8 are a plan view and section, respectively, on one of the bearing 25 shoes, and

Fig. 9 is an under elevation of the face plate carried on the driving shaft.

The present invention relates to universal couplings. The invention is illustrated as embodied in universal shaft couplings applied to a rolling mill drive.

The object of the invention is to provide a coupling of this character in which the wear is so distributed that the parts will not readily wear out, and in which the parts subject to the greatest wear may be easily removed and renewed. The invention also relates to certain other features hereinafter more particularly pointed out, the advantages of which will be apparent to those skilled in this art from the following description.

Referring to the illustrated embodiment of the invention, the driving shaft 2 and mill roll shaft 3 are connected by coupling spindle 4, which permits the mill roll to be moved up and down. The coupling spindle is connected with the two shafts by flexible couplings embodying the invention. As shown in the drawings, the male members of the couplings are formed on the spindle 4, while the female members are carried by the drive and mill roll shafts. It will be understood, however, that the male and fe-

male members of the couplings might be 55 interchanged. The two couplings shown in the drawings are of the same structure, and corresponding reference characters are applied to each.

Each coupling comprises a head 5 bolted 60 and keyed to the face plate 6 which is carried on the shaft 2 or 3. The head 5 has two parallel jaws 7 and 8 between which lie tongues 9 formed on opposite ends of the spindle 4. The tongues 9 have flat bearing 65 faces 10. Interposed between the jaws and tongue are bearing shoes 11, two pairs of shoes being employed in each coupling. The shoes 11 are mounted in wear plates 12, which are inset in the faces of the jaws 7 70 and 8. The bearing shoes 11 have spherical faces 13, which engage in the recess 14 in the wear plates 12 to form ball and socket joints. The other faces 15 of the bearing 75 shoes are flat to give a sliding fit with the tongue 9. The bearing shoes are furnished with lubricating channels 16 which may be fed with oil through the oil holes 17 in the spindle 4.

The driving pressure against the bearing 80 surfaces of the coupling, is distributed over the faces of the bearing shoes 13 which, by virtue of the ball and socket connection, are self-adjusting to distribute the pressure substantially uniformly over their bearing surfaces. In this way localized and excessive wear on the parts is prevented. The coupling may be disassembled for renewal or for repair by slipping off the retaining sleeve 20, which serves to hold the tongue 90 in place between the jaws.

In the illustrated embodiment, the coupling which is attached to the driving shaft, which is at the lower end of the spindle 4 in usual rolling mill practice, is provided with a thrust bearing block 21 fitting 95 against a bearing block 22 on the end of the spindle.

By forming the socket bearings 14 in the wear plates 12, instead of directly in faces 100 of the jaws 7 and 8, such sockets may be more accurately formed. These wear plates also provide effective means for adjustment to take up wear, which occurs between the sockets and the shoes. This may be readily effected by inserting shims of the necessary thickness between one or both of the wear plates and their seats on the jaws. This is 105

of very considerable importance in maintaining the coupling in proper condition notwithstanding wear.

It will be noted that I provide a pair of bearing shoes at each side of the longitudinal axis of the coupling, whereby the coupling is equally effective in either direction of rotation.

While the preferred embodiment of the invention has been specifically illustrated and described, it is to be understood that the invention is not limited to its illustrated embodiment but may be embodied in other structures of universal couplings within the scope of the following claims.

I claim:

1. A universal coupling comprising two members to be coupled, one of said members having jaws and the other member having a tongue extending between the jaws, and bearing shoes interposed between the tongue and jaws having ball and socket mounting in one member and a sliding fit with the other member; substantially as described.
2. A universal coupling comprising two members to be coupled, one of said members having jaws and the other member having a tongue extending between the jaws, and bearing shoes interposed between the tongue and jaws eccentric to the longitudinal axis of the coupling, said bearing shoes having spherical bearing surfaces engaging one member and flat bearing surfaces engaging the other member, substantially as described.
3. A universal coupling comprising two members to be coupled, one of said members having jaws and the other member having a tongue extending between the jaws, and bearing shoes interposed between the tongue and jaws eccentric to the longitudinal axis of the coupling and having ball and socket connections with one of said members, substantially as described.
4. A universal coupling comprising two members to be coupled, one of said members having jaws and the other member having a tongue extending between the jaws, and bearing shoes disposed in pairs on opposite faces of the tongue and at each side of the longitudinal axis of the coupling and having ball and socket mountings in one of said members; substantially as described.
5. A universal coupling comprising two members to be coupled, one of said members

having jaws and the other member having a tongue extending between the jaws, means for removably retaining the tongue between the jaws, and bearing shoes interposed between the tongue and jaws and having ball and socket mountings in one of the members and so disposed as to be removable when the tongue is removed from between the jaws; substantially as described.

6. A universal coupling comprising two members to be coupled, one of said members having jaws and the other member having a tongue extending between the jaws, said tongue having flat bearing surfaces at opposite sides thereof, and bearing shoes having ball and socket mountings in the jaws eccentric to the longitudinal axis of the coupling and having flat faces slidably fitting against the faces of the tongues; substantially as described.

7. A universal coupling comprising two members to be coupled, one of said members having jaws and the other member having a tongue extending between the jaws, and bearing shoes interposed between the tongue and jaws and having ball and socket mounting in one member and a sliding fit with the other, there being a pair of the shoes at each side of the longitudinal axis of the coupling; substantially as described.

8. A universal coupling comprising two members to be coupled, one of said members having jaws and the other member having a tongue extending between the jaws, bearing shoes interposed between the tongue and jaws having ball and socket mounting in one member and a sliding fit with the other member, the socket mountings being formed in wear plates seated on said jaws; substantially as described.

9. A universal coupling comprising two members to be coupled, one of said members having jaws and the other member having a tongue extending between the jaws, bearing shoes interposed between the tongue and jaws having ball and socket mounting in one member and a sliding fit with the other member, the socket mountings being formed in wear plates adjustably seated on said jaws; substantially as described.

In testimony whereof, I have hereunto set my hand.

LLOYD JONES.
